UNITED STATES PATENT OFFICE.

THOMAS C. SHAW, OF NEAR HONEA PATH, SOUTH CAROLINA.

BULLETIN-BOARD.

1,247,886.

Specification of Letters Patent. Patented Nov. 27, 1917.

Application filed January 6, 1917. Serial No. 140,908.

To all whom it may concern:

Be it known that I, THOMAS C. SHAW, a citizen of the United States, residing near Honea Path, in the county of Abbeville and State of South Carolina, have invented certain new and useful Improvements in Bulletin-Boards, of which the following is a specification.

The present invention relates to bulletin-boards and similar devices, and more particularly to those of the type disclosed and covered by the claims of my Patent No. 1,206,148, dated November 28, 1916.

The object is to provide effective paper or article clamping means that will maintain their proper relation and operative condition, this clamping means being simple.

In the accompanying drawings

Figure 1 is a view in front elevation of the bulletin-board having the improved structure.

Fig. 2 is a side elevation of the same.

Fig. 3 is a vertical sectional view on an enlarged scale through the case, showing one embodiment of the clamping means.

Fig. 3^a is a detail perspective view of one of the clamps and carrier collars.

Fig. 3^b is a cross sectional view on the line 3—3 of Fig. 3.

Fig. 4 is a view similar to Fig. 3, but illustrating a modified form of paper clamping means.

Fig. 5 is a cross sectional view through the structure shown in Fig. 4.

Fig. 6 is a detail perspective view of the carrier collar illustrated in Figs. 4, and 5.

Fig. 7 is a vertical sectional view illustrating another embodiment of the invention.

Fig. 8 illustrates still another form of paper holding clip.

Fig. 9 is a view in vertical section of a bulletin-board illustrating still another embodiment of the invention.

Fig. 10 illustrates a structure similar to Fig. 9, but having a modified form of clamping means.

Fig. 10^a is a detail view illustrating a paper engaging clip of another formation.

Fig. 11 is a cross sectional view of the structure shown in Fig. 10^a.

Fig. 12 is a detail perspective view illustrating the manner of fastening the standards illustrated in Fig. 10^a.

Fig. 13 is a detail cross sectional view of the structure illustrated in Fig. 9.

Fig. 14 is a detail cross sectional view of the structure illustrated in Fig. 10.

Fig. 15 is a view similar to Fig. 14, but showing the carrier collar in open condition.

Fig. 16 is a vertical sectional view through a casing showing a modified form of structure.

Fig. 17 is a detail sectional view at right angles thereto.

Fig. 18 is a horizontal sectional view.

Fig. 19 is a detail perspective view of a portion of one of the securing strips.

Similar reference numerals designate corresponding parts in all the figures of the drawings.

In the embodiment illustrated, a case 16 is employed, which may be of any suitable form, that shown being supported by standards 17 that are mounted on suitable bases or feet 18. This case has a top wall 19, a bottom 20, a front transparent wall 21, and a rear wall 22 that can be opened, as will be readily understood. Mounted within the case and spaced from both the front and rear walls 21 and 22 are vertical standards 23. Slidable on these standards are carrier collars 24 that may be held in any suitable position by set screws 25. These collars have secured to their front side channel pieces 26 forming spaced ears, to and between which are pivoted paper engaging clips 27, the pivots being illustrated at 28. These clips, as will be clear by reference to Fig. 3 are arranged to coöperate with the rear side of the transparent wall 21 to clamp thereagainst papers or other articles to be displayed, and in order to insure the proper engagement, leaf springs 29 secured to the collars within the channel pieces 26 bear against the clips 27. As illustrated in Fig. 3^b, the standards 23 in this particular form of construction are formed of channel bars.

It is believed that the manner in which the device is used will be readily understood by reference to Figs. 1 and 3. The papers or other documents or articles to be displayed, are placed against the rear face of the transparent wall 21, and the clips are arranged so that they will properly bear against the same to hold said papers flat against the wall. It will be evident that these clips are individually movable, so that they can be arranged to suit different conditions of use.

In Figs. 4, 5, 6, a slightly different em-

bodiment is illustrated. In this form of construction, the standards 23^a are tubular, and are held in place by pins 30, which are located in the top and bottom walls 19 and 20, the pins projecting into the bores of the tubes. The carrier collars are designated 24^a, and have their openings corresponding in cross sectional form to the tubes 23^a. The said carrier collars are held in adjusted relation by set screws 25^a. In this embodiment of the invention the collars have flattened front surfaces 26^a and secured thereto are spring clips 27^a.

In the embodiment illustrated in Fig. 7, the standards, which are designated 23^b are tubular in form and are held in place by pins 30^b. Slidable upon these standards are carrier collars 24^b held against movement by set screws 25^b, and the clamping devices comprise heads 26^b which are held against the transparent face 21 by springs 27^b secured thereto and to the collars 24^b. The heads preferably have stems 28^b arranged within the springs, and terminate short of the collar 24^b.

The structure illustrated in Fig. 8 is substantially the same as that shown in Fig. 7, with the exception that the collars 24^c carry bowed springs 26^c secured at their centers to the collars and having flattened terminals 27^c that coöperate with the transparent front wall 21.

In the structure illustrated in Fig. 9, the standards designated 23^d, as shown in Fig. 13, comprise T-bars. These standards have carrier collars 24^d surrounding them and carry spring clips 26^d that coöperate with the transparent front wall in the usual manner.

In the structure illustrated in Fig. 10, the standards 23^e are square in cross section, as illustrated in Fig. 15, and the carrier collars 24^e are split, forming clamping side arms or portions which are drawn together by connecting screws 25^e. These carrier collars are provided with clamping clips 26^e.

In the embodiment illustrated in Fig. 10^a, the standards 23^f are square in cross section as will be clear by reference to Fig. 11, the carrier collars 24^f being also square and having set screws 25^f for holding them. The paper clamping means 26^f comprise bowed springs secured at their centers to the collars 24^f and having their free ends coöperating with the glass or other transparent wall.

In this embodiment illustrated in Figs. 16-19 inclusive, the casing includes a top 19^g, a bottom 20^g, a front transparent wall 21^g and a rear wall 22^g. Vertical standards 23^g are provided, on which are carrier collars 24^g that may be held in place by set screws 25^g. These collars have secured to their front side suitable clips 27^g that coöperate with the transparent wall 21^g in the manner already described.

In this embodiment, the standards 23^g are in sections, the upper ends being engaged in sockets 28^g formed in a channel strip 29^g that is secured to the inner side of the top 19^g by screws 30^g.

With this arrangement, it will be evident that the channel strips can be placed in any desired position. The ends of the standards engaged in the sockets 28^g, are held by set screws 31^g. The lower ends of the standards are in like manner engaged in a lower channel strip 32^g secured to the bottom 20^g, said lower ends of the standards being held against accidental detachment by set screws 33^g. The adjacent ends of the sections of said standards 23^g are engaged in sockets 34^g formed in opposite sides of a hollow reinforcing bar 35^g that extends horizontally across the casing between the two ends. This reinforcing bar is illustrated as square in cross section, though the cross sectional configuration is relatively unimportant. The bar has its ends suitably fastened to the end walls, as for example by corner braces 36^g.

From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention.

Having thus fully described my invention, what I claim as new, and desire to secure by Letters Patent, is:—

1. In a device of the character set forth, the combination with a structure including a top, a bottom and a side wall, of a hollow standard located alongside the side wall, means carried by the top and bottom and projecting into the standard for holding the same, a carrier slidable upon the standard, and means mounted on the carrier and coacting with the wall for clamping thereagainst an article to be held.

2. In a device of the character set forth, the combination with a casing including a top, a bottom, ends, and a side wall, of an upper securing strip mounted on the top and a lower securing strip mounted on the bottom, each of the strips having a plurality of sockets, standards having their ends engaged in the sockets of the strips, collars surrounding and slidable on the standards, and article engaging clips coacting with the side wall and carried by the collars.

3. In a device of the character set forth, the combination with a casing including a top, a bottom, ends, and a side wall, of channel strips mounted on the top and bottom and including spaced sockets, standards having their ends engaged in the sockets,

means securing the said ends in place, collars slideable on the standards, and article engaging clips coacting with the side wall and carried by the collars.

- 5 4. In a device of the character set forth, the combination with a casing including a top, a bottom, ends, and a side wall, of a reinforcing bar extending between the ends and disposed in spaced relation to the top and bottom, spaced standards engaged with the top and bottom and with the reinforcing bar, collars slideable on the standards, and article engaging clips coacting with the side wall and carried by the collars.
- 10 5. In a device of the character set forth, the combination with a casing including a top, a bottom, ends, and a side wall, of

channel strips mounted on the top and bottom and having spaced sockets, a reinforcing bar extending across the casing and engaged with the ends in spaced relation to the top and bottom, said reinforcing bar having sockets, standards engaged in the sockets of the channel strips and reinforcing bar, means for securing said standards in place, collars slideable upon the standards, and clips coacting with the side wall and carried by the collars.

In testimony whereof I affix my signature in the presence of two witnesses.

THOMAS C. SHAW.
